UNITED STATES PATENT OFFICE.

REUBEN W. EHLING, OF DUNCANNON, PENNSYLVANIA.

MERRY-GO-ROUND.

Application filed April 30, 1923. Serial No. 635,740.

This invention relates to toy carousels or merry-go-rounds, and one of the principal objects of the invention is to provide a device of this nature which may be readily knocked down and packed away in a compact package.

Another object is to produce a device of this character having a novel driving mechanism.

Another object is to produce a device of this nature having novel means for leading in energy to the driving mechanism.

Another object is to produce a device of this nature which shall be simple of construction, comparatively inexpensive to manufacture and assemble, and highly efficient for the purpose for which it is designed.

With these and other objects in view, the invention consists in certain novel construction and combination and arrangement of parts, the essential features of which are hereinafter fully described, are particularly pointed out in the appended claim, and are illustrated in the accompanying drawings, in which:—

Figure 1 is a side elevation of the toy carousel, with the canopy in section.

Figure 2 is a top plan view of the base and the driving mechanism per se:

Figure 3 is a section in elevation, taken substantially on the line 3—3 in Figure 2.

Like characters of reference refer to like parts in all views.

Referring to the drawings in detail, 10 represents a base upon which the entire structure is supported. The base as shown is square, but may be of any suitable shape and material to support the mechanism hereinafter described. Mounted on the base 10, is a small electric motor 11, the lead wires 12, of which run into the base 10, and are connected to a pair of brass strips 13 or other suitable contact members secured to the side walls of a mortice 14 formed in the base 10. A strip of wood 15 is formed with a longitudinally extending tenon 16 on the sides of which brass contact strips 17 are secured. Wires 18 connect the strips 17 to a switch 19 of any suitable standard construction, the switch having suitable connections to binding posts 20 to which may be attached the leads from any suitable source of electrical energy. It will be seen that by the above construction, the lead-in device 15 can be separated from the base 10 for readily packing the same.

Secured to the base 10 by screws, bolts or other suitable and readily removable means is a supporting member 21 provided with a socket 22 in which is removably secured by 60 set screws 23, an upright tube 24. Rising from the member 21 is also a bracket or framework 25 which rotatably supports a short shaft 26 carrying a pulley 27 which is connected for driving from the motor 11. 65 On the other end of the shaft 26, a gear 28 is secured, said gear meshing with the teeth on a gear 29 mounted on a vertically supported shaft 30 having its bearings in the bracket 25. On the upper end of shaft 30 is 70 a small gear 31' which drives the revolving parts of the carousel which will now be described.

The revolving platform and parts are suspended from a rod or shaft 31 which is a 75 sliding fit for the tubular member 24 in which it rotates. The rod 31 has secured to it a driving gear 33 which is removable from the rod and the lower face of which rests on the top of tube 24 and forms a suitable bearing for the rotatable parts. This gear 33 meshes with the aforementioned driving gear 31' by which it is driven. Secured to the rod 31 above the gear 33 is a standard-supporting member 34 and is in the 80 form of a hubbed disk and secured to the shaft 31 by a set screw. At its top, the rod 31 supports a brace supporting member 35 which is also secured to the member 31 by a set screw. 85

Secured to the disk-like standard-supporting member 34 by bolts 36 or other suitable means are a plurality of radially disposed standards or beams 37. Each of these beams 37 is drilled near its end and at a point between its ends and supports a pair of depending rods or hangers 38 which support at their bottom, the platform structure. The rods 38 are threaded at both ends and provided with nuts 39 above and below the 90 beams 37 and the platform presently to be described, whereby the rods are held rigidly with respect to the other members. Secured in apertures in the head member 35 are the ends of a plurality of braces 40, 95 there being one for each beam 37, and extending toward the end of its respective beam to which it is secured by being inserted in an aperture in a metal tab or clamp 41 held fast by the upper and outer nut 39 of 100 the respective beam. 105

The rotating platform comprises a plu-

rality of arcuate sections 42 which are held together by strips 43 bolted at opposite ends to the abutting ends of the sections 42. Mounted on this platform are a plurality of 5 animals 44 which may be of any suitable type and which are removably held in place by depending central standards or rods 45 which extend through the sections 42 and are provided with securing nuts 46 whereby they 10 may be firmly engaged with the platform. If desired, a number of benches or seats 47 may also be placed on the platform, and as they have very broad bases will not need means for holding them in place.

15 A suitable canopy or tent cover 48 is provided which rests down on the braces and over the top edge, giving the entire device an attractive appearance.

The operation of the device is so obvious 20 from the foregoing description of parts that no extended description thereof will be given; but it is thought that it will be readily seen that I have constructed a device which is not only amusing in that it moves 25 and is controllable by the child, but is also highly instructive in that the entire device may be taken apart and put together again, thereby calling forth the child's imagination and perception, and fostering any mechanical instincts which he may possess.

While I have described what I deem to 30 be the most desirable embodiment of my invention, it is obvious that many of the parts may be varied without in any way departing 35 from the spirit of my invention, and I therefore do not limit myself to the exact details of construction herein shown nor to any-

thing less than the whole of my invention limited only by the appended claim.

What I claim is:—

40 A collapsible toy carrousel comprising a base member, a tubular standard vertically disposed and secured on said base member, a vertical supporting shaft, an annular flange and bearing hub therefor secured to said 45 shaft adjacent the lower end thereof, a ring gear and bearing hub therefor secured to said shaft with the hub thereof abutting the hub on said annular flange, the remaining lower free end of said shaft telescopically 50 journaled in the upper end of said tubular standard, a plurality of radially disposed beams having their inner ends secured to said annular flange, an apertured annular 55 crown flange secured to the upper end of said shaft for anchoring the extended free ends of said beams thereto by means of a plurality of inclined bracing hooks and apertured attaching plates therefor, a character supporting platform comprising a plurality 60 of arcuately formed segment members, tie plates for detachably securing said members in circumferential endwise engagement, a plurality of threaded rods and lock nuts therefor having their upper ends detachably 65 secured to said beams, the lower ends of said rods secured in like manner to the said segment members comprising said platform, and means associated with said ring gear for rotating said shaft, radial beams and sup- 70 porting platform.

65 In testimony whereof I affix my signature.

REUBEN W. EHLING.
